LOW-CLEARANCE ANTENNA

Paul J. Selgin, Fort Wayne, Ind., assignor, by
mesne assignments, to Farnsworth Research
Corporation, a corporation of Indiana

Application April 12, 1947, Serial No. 741,109

5 Claims. (Cl. 250—33)

1

This invention relates to high frequency antennae and particularly to an antenna for radiating a vertically polarized wave substantially uniformly in all horizontal directions.

It is conventional practice to establish radio communications between a moving vehicle such as a train and another train or a fixed station. For a radio communications system of this type an antenna is required which is usually mounted on the roof of a vehicle such as a railroad car. Since the train must be able to pass under bridges or through tunnels of fixed clearance, it is desirable to provide an antenna which has low overall vertical dimensions and a high efficiency comparable to that of a conventional half-wave dipole antenna. The horizontal radiation pattern developed by the antenna should preferably be substantially circular.

It has been suggested to provide an antenna comprising a lower cone and an upper disc. This so-called "discone" antenna has a very wide frequency range. However, the height of the conventional discone antenna is approximately a quarter wave length at the cutoff frequency which is too high for a low clearance antenna for vehicles. It has also been proposed to provide a horn or radiating wave guide consisting of two inverted cones having their apices adjacent to each other. Another conventional antenna of this general type has two radiating cones coupled to the two conductors of a coaxial transmission line. The two cones of the biconical antenna are of equal diameter, and the overall vertical height of the antenna is not low enough for the purposes referred to. Furthermore, certain difficulties have been experienced with a biconical antenna. When the two cones are supported by connecting their outer rims by means of insulating rods, the horizontal radiation pattern is not uniform. Actually the horizontal radiation pattern about the dielectric supporting rods resembles an optical interference pattern which is very undesirable.

It is furthermore conventional practice to provide a high frequency antenna with an impedance matching network for matching the radiation impedance of the antenna to the impedance of the transmission line which feeds the antenna. The impedance matching network preferably should be adjustable while the antenna is in operation so that waves of different frequencies may be either radiated from or received by the antenna.

It is an object of the present invention, therefore, to provide a high frequency antenna which

2

combines low vertical overall dimensions with an efficiency comparable to that of a conventional half-wave dipole.

Another object of the invention is to provide 5 a novel high frequency antenna which will radiate a vertically polarized wave having a substantially circular radiation pattern in a horizontal plane.

A further object of the invention is to provide 10 an antenna suitable for intercepting and radiating high frequency energy and having a low reactive impedance with an impedance matching network which may be adjusted during operation of the antenna for properly matching the impedance of the transmission line feeding the antenna to that of the antenna at a desired frequency.

In accordance with the present invention there 15 is provided an antenna comprising a first annular antenna element and a second annular antenna element. There are further provided a transmission line and impedance means for coupling the transmission line to the two antenna elements. The first antenna element has a diameter 20 which is smaller than that of the second antenna element. Preferably the second or lower antenna element has a diameter of the order of one half the operating wave length of the antenna, while the total height of the antenna may be of the order of one-sixteenth of its operating wave length. Further in accordance with the present invention the antenna is provided with 25 an adjustable impedance matching network, such as a reactive network, for coupling the transmission line to the two antenna elements.

30 For a better understanding of the invention, together with other and further objects thereof, reference is made to the following description, taken in connection with the accompanying drawing, and its scope will be pointed out in the 35 appended claims.

In the accompanying drawing:

Fig. 1 is a cross sectional view of an antenna embodying the present invention;

Fig. 2 is a top plan view of the antenna of Fig. 45 1; and

Fig. 3 is a schematic electric diagram of the 50 antenna of the invention illustrating the adjustable impedance matching network for coupling a transmission line to the antenna.

Referring now to the drawing and particularly to Figs. 1 and 2, there is illustrated a high frequency antenna including lower antenna element 1 and upper antenna element 2. As shown in Fig. 1, the lower antenna element 1 is of substan-

entially conical shape. The upper antenna element 2 has also been illustrated as being of substantially conical shape, the apices of the two cones formed by antenna elements 1 and 2 are arranged adjacent to each other. However, the shape of the upper antenna element 2 is not critical, and accordingly, antenna element 2 may, for example, consist of a flat disc instead of a cone.

Lower antenna element 1 is provided with horizontal supporting plate 3 to which it may be secured by suitable rivets or screws indicated at 4. Thus, lower antenna element 1 and supporting plate 3 form an enclosed space. Upper antenna element 2 is provided at its outer rim with reinforcing ring-shaped tube 5 to provide mechanical stability.

The antenna consisting of elements 1 and 2 is connected through coaxial transmission line 6 to a high frequency translator 7 which may either be a transmitter or a receiver for radiating an electromagnetic wave into space or for intercepting a wave. Coaxial transmission line 6 consists of inner conductor 8 and outer conductor 10 which preferably is maintained at ground potential as is conventional. Inner conductor 8 of transmission line 6 is coupled to upper antenna element 2, while outer conductor 10 is connected to lower antenna element 1 in a manner to be described hereinafter.

When high frequency translator 7 consists of a transmitter, the antenna will radiate a vertically polarized wave having a substantially circular radiation pattern in a horizontal plane. It will be noted that antenna elements 1 and 2 as illustrated consist of two very flat cones while cone 2 may also consist of a disc so that the overall vertical height of the antenna may be made extremely small. Thus, the total height of the antenna need be no more than one-sixteenth of the operating wave length. The diameter of lower antenna element 1 should preferably be slightly less than one-half the operating wave length, while the diameter of upper antenna element 2 should be approximately one-half that of the lower antenna element 1.

The antenna as described has a low impedance which is reactive. Accordingly, the radiation impedance of the antenna depends upon the frequency of the wave intercepted or radiated. It is desirable, therefore, to provide a reactive impedance matching network between coaxial transmission line 6 and antennae 1 and 2 which should be adjustable for different frequencies.

The impedance matching network is preferably disposed in lower antenna element 1 and further comprises means for supporting the upper antenna element 2 from the lower element 1. This construction makes it possible to support the two antenna elements in such a manner that a radiated wave does not form an interference pattern which would be the case if any obstructions such as insulating supports were arranged in the space between elements 1 and 2.

For the purpose of electrically connecting outer conductor 10 of transmission line 6 to the lower antenna element 1, there is provided cup-shaped housing 12 consisting of a conducting material and secured to lower antenna element 1 by screws indicated at 13. Cover 14 which also consists of a conducting material, such as a metal, is threaded into cup-shaped housing 12. An outer sleeve 15 consisting of an insulating material is secured to cover 14 by screws 16. The upper portion of outer sleeve 15 is secured to upper antenna element 2 through bushing plate 17 which con-

sists of a conducting material. Upper antenna element 2 is accordingly supported by housing 12, cover 14 and outer sleeve 15.

Inner conductor 8 of transmission line 6 is connected to lower condenser plate 20 as illustrated. Condenser plate 20 is secured to housing 12 through collar 21 which consists of an insulating material. Condenser plate 20 is thus fixed to housing 12. Upper condenser plate 22 is secured to inner sleeve 23 which is slidably arranged in outer sleeve 15 and consists of insulating material. Upper condenser plate 22 is electrically coupled to upper antenna element 2 through inductance element 24 provided in the space formed by inner sleeve 23. Stud 25 which consists of a conducting material is electrically connected to inductance element 24 and may be screwed into inner sleeve 23 or otherwise secured thereto. Stud 25 extends through outer sleeve 15 and is screwed into bushing 26 which in turn is threaded into bushing plate 17. Set screw 27 is provided in bushing 26 for locking stud 25. Another set screw 28 is provided in housing 12 for locking it to cover 14.

An impedance matching network is thus provided for coupling coaxial transmission line 6 to antennae 1 and 2. As shown schematically in Fig. 3, inner conductor 8 is connected to adjustable condenser 30 which is represented in Fig. 1 by condenser plates 20 and 22. Condenser 30 is coupled to upper antenna element 2 through inductance element 24 and stud 25 as shown in Fig. 3. Another condenser 31 is provided between the junction point of condenser 30 and inductance element 24 on the one hand and housing 12 on the other hand as shown schematically in Fig. 3. Thus, condenser 31 is effectively connected between inner conductor 8 and lower antenna element 1. Condenser 31 represents the capacitance between condenser plate 22 and cover 14.

It will now be seen that condensers 30 and 31 are individually adjustable. Thus, in order to adjust the capacitance of condenser 31, set screw 27 is loosened and stud 25 is rotated thereby to move inner sleeve 23 with respect to outer sleeve 15. Consequently the distance between condenser plate 22 and cover 14 may be varied or adjusted. It will be obvious that by this adjustment the distance between condenser plates 20 and 22 will be varied simultaneously. However, the distance between condenser plates 20 and 22 may be adjusted by loosening set screw 28 and rotating upper antenna element 2 which may be effected, for example, by gripping tube 5. Accordingly, upper antenna element 2, outer sleeve 15, cover 14, inner sleeve 23 and upper condenser plate 22 will rotate in unison with respect to housing 12 thereby to adjust the distance between condenser plates 20 and 22. This in turn will adjust the capacitance of condenser 30.

It will accordingly be evident that the impedance matching network including condensers 30, 31 and inductance element 24 may be adjusted while the antenna is in operation and mounted, for example, on the roof of a railroad car or other vehicle. It is also feasible to provide suitable stops for adjusting the distances between condenser plates 20 and 22 on the one hand and between condenser plate 22 and cover 14 on the other hand if the antenna is intended to operate at a predetermined frequency. In that case the adjustment may be effected while the antenna is assembled.

Experiments carried out with the antenna of

the invention have revealed that the antenna has an efficiency comparable to that of a conventional vertical half-wave dipole antenna. Since the overall height of the antenna may be as low as one-sixteenth of the operating wave length, the antenna is particularly suitable for use on moving vehicles where a low clearance antenna is required. In spite of its small height the efficiency of the antenna is not impaired.

While there has been described what is at present considered the preferred embodiment of the invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. An antenna comprising a first antenna element, a second antenna element, a line having first and second conductors, a housing for electrically connecting said second conductor to said second element and fixed to said second element, a first condenser member connected to said first conductor and fixedly disposed in said housing, a second condenser member, means for electrically coupling said second condenser member to said first element, and movable means mounted on said housing and connected to said second condenser member for adjusting the distance and the capacitance between said condenser members, thereby to provide an adjustable impedance matching network between said antenna and said line.

2. An antenna comprising a first antenna element, a second antenna element, a line having first and second conductors, a housing for electrically connecting said first conductor to said second element and fixed to said second element, a first condenser plate connected to said second conductor and fixedly disposed in said housing, a second condenser plate, a cover for said housing electrically connected to said second element and insulated from said second condenser plate, said second condenser plate being arranged to have its distance from said cover adjusted to vary the capacitance between said second condenser member and said cover, said cover being arranged to be moved in unison with said second condenser plate for adjusting the distance and capacitance between said condenser plates, thereby to provide an adjustable impedance matching network between said antenna and said line.

3. An antenna comprising an upper antenna element, a lower antenna element, a coaxial transmission line having an inner and an outer conductor, a housing for electrically connecting said outer conductor to one of said elements and disposed within said one element, a cover for said housing electrically connected thereto and mechanically connected to and insulated from the other of said elements, a first condenser plate connected to said inner conductor and fixedly disposed in said housing, a second condenser plate electrically coupled to said first condenser plate and to said cover, means for electrically connecting said second condenser plate to said other element and for adjusting its distance from said cover to adjust the capacitance therebetween, and means for simultaneously moving said cover and said second condenser plate to adjust the distance and the capacitance between said condenser plates,

thereby to provide an adjustable impedance matching network between said antenna and said transmission line.

4. An antenna comprising an upper antenna element, a lower antenna element of substantially conical shape, the diameter of said lower element being larger than that of said upper element, a coaxial transmission line having an inner and an outer conductor, a cup-shaped housing for electrically connecting said outer conductor to said lower element and disposed within said lower element, a cover threaded into said housing and electrically connected thereto, an insulating support fixed to said cover and to said upper element, a first condenser plate connected to said inner conductor and fixedly disposed in said housing, a second condenser plate electrically coupled to said first condenser plate and to said cover, means for electrically connecting said second condenser plate to said upper element and for adjusting its distance from said cover to adjust the capacitance therebetween, thereby to adjust the distance and the capacitance between said condenser plates by rotating said upper element and said cover simultaneously with said second condenser plate.

5. An antenna comprising an upper antenna element, a lower antenna element of substantially conical shape, the diameter of said lower element being larger than that of said upper element, a coaxial transmission line having an inner and an outer conductor, a cup-shaped housing for electrically connecting said outer conductor to said lower element and disposed within said lower element, a cover threaded into said housing and electrically connected thereto, an insulating support fixed to said cover and to said upper element, a first condenser plate connected to said inner conductor and fixedly disposed in said housing, a second condenser plate electrically coupled to said first condenser plate and to said cover, a stud threaded into said upper element, an inductance element for electrically connecting said second condenser plate to said stud and to said upper element, an insulating member for securing said stud to said second condenser plate, thereby to adjust the distance and the capacitance between said cover and said second condenser plate by rotating said stud and to adjust the distance and the capacitance between said condenser plates by rotating said upper element to rotate said cover simultaneously with said second condenser plate.
